BORING AUGER FOR HORIZONTAL EARTH BORING MACHINES

Albert R. Richmond, West Salem, Ohio, assignor to The
Richmond Manufacturing Company, Ashland, Ohio

Filed Aug. 6, 1970, Ser. No. 24,332

Term of patent 14 years

Int. Cl. D15—04

U.S. Cl. D39—1

Fig. 1.

Fig. 2.

Fig. 3.

Fig. 4.

Fig. 5.

Fig. 6.

FIG. 1 is a top plan view of a boring auger for a horizontal earth boring machine showing my new design;

FIG. 2 is a side elevation thereof;

FIG. 3 is an elevation of the opposite side;

FIG. 4 is a bottom plan view thereof;

FIG. 5 is a top perspective view of the boring auger of FIG. 1; and

FIG. 6 is a bottom perspective view of the boring auger of FIG. 1.

I claim:

The ornamental design for a boring auger for horizontal earth boring machines, as shown.
